DESIGN.

W. J. KEEP & C. WIPFLER.

HEATING STOVE.

No. 18,700.

Patented Oct. 23, 1888.

UNITED STATES PATENT OFFICE.

WILLIAM J. KEEP AND CHARLES WIPFLER, OF DETROIT, MICHIGAN, AS
SIGNORS TO THE MICHIGAN STOVE COMPANY, OF SAME PLACE.

DESIGN FOR A HEATING-STOVE.

SPECIFICATION forming part of Design No. 18,700, dated October 23, 1888.

Application filed April 4, 1888. Serial No. 269,626. Term of patent 7 years.

To all whom it may concern:

Be it known that we, WILLIAM J. KEEP and CHARLES WIPFLER, citizens of the United States, residing at Detroit, in the county of 5 Wayne and State of Michigan, have invented a certain new and useful Design for Heating-Stoves, of which the following is a specification, reference being had therein to the accompanying photograph.

10 This design is more particularly designed for heating-stoves.

The leading features of this design reside, in addition to the ornamentation of the stove as an 15 entirety, in the peculiar shape and ornamentation of the segregable parts thereof, as shown in the accompanying photograph.

Referring to the said photograph, A designates the leg-base, ornamented with scroll-work, as shown, said scroll-work being formed 20 on each side of the leg-base as follows: A large scroll, *a*, the center of which simulates a spread leaf, is at each end, the outer convolute of said scroll extending from the bottom of the said scroll *a* upward and toward the center of the 25 base, passing through the convolutes of a smaller scroll, *b*, forming a part of the main scroll, the terminals of the scrolls at the center of the base extending upwardly and from each other and terminating each in a leaf, *c*.

30 Following the upwardly-extending outer convolutes of the scroll *a*, and filling the space between said convolute and the outer convolute of the scroll *b*, are the flame-shaped ornaments *d*. The corners of the base above the upper 35 ends of the legs are ornamented by the curved beads *e*.

The legs *B* have serrated edges simulating the edges of growing leaves, and at the toe are 40 ornamented by branched leaves, from the center of which springs the upwardly-extending flame-shaped ornament *f*.

The ash-pit section *C* is substantially rectangular in shape, provided at the sides with the foot-rail *g*, ornamented at its ends by the rosettes, as shown, and by circumferential alternating plain and ribbed portions *h*. The 45 curved bands *i*, embracing said foot-rail, are ornamented by similar transverse plain and ribbed portions. The ends of the bands simulate a three-leaved clover.

The ash-pit door *D* is of ogee shape in vertical cross-section, ornamented in front by ornamental letters and scrolls, beneath this by the flutes *j*, and at the end by the scroll *k*, which spreads outward at the upper end, giving the 55 appearance of the petals of a flower.

The cylinder *E* is formed of the upper and lower side plates, *E' F'*, respectively, and the upper and lower front plates, *G' H'*, respectively.

60 The cylinder *E*, near its vertical center, is apparently divided into two parts by the ornamental band *l*, rounded as shown, the upper portion being ribbed vertically and the lower half plain.

65 The side plate or panel, *F'*, of the lower portion of the cylinder is ornamented at the lower end by the outwardly-inclined portion *m*, fluted vertically, and at the sides by vertically-ribbed columns. This side plate is further ornamented 70 by the central scroll, *n*, the central convolute of which is divided by transverse lines to give the appearance of knobs. Appearing to rest upon one of the branches of a convolute of this scroll is the foot of the figure *F*, provided with 75 a wing, *o*, and from his mouth issues a volume of flame and smoke, which curls around and fills the upper portion of the panel. Beneath the scroll *n*, and appearing to form a sort of support therefor, is finer scroll-work.

80 The upper side plate or panel, *E'*, has at each corner a small scroll inclosing a rosette, the outer convolutes of the small scrolls approaching each other and forming a further ornamentation, as shown.

85 Nestling within the center of a large scroll inclosed between the small corner scrolls is the nondescript animal *p*, simulating in appearance part fish and part bird.

The front lower plate or panel, *H'*, of the 90 cylinder is ornamented by the nondescript animal *q*, the feet or claws of which rest within the convolutes of a scroll, and from his mouth issues the flame *r*, while his tail has the appearance of inversely-extended scrolls, one of 95 which terminates in the flame-shaped ornament *s*. Between the wing of the animal and the flame which issues from his mouth are the scrolls *t*.

100 Beneath the front lower plate or panel, *H'*,

is the door I, the lower corners of which are curved and the upper corners sharp.

The upper door, J, is ornamented by irregularly-arranged bars. In the center is the circular plain ring, within which is the band n', formed with radially-arranged ribs, as shown.

At the top of the upper front plate or panel, G', above the door-opening therein, are the rosettes v, between which is a fanciful ornament.

10 Above and below the cylinder are the bands K L, respectively, each being ornamented by scroll-work, as shown.

Above the band K is a plain rectangular molding, M, above which is the cover N, having at its lower edge the rectangular plain molding O, and consisting, above said molding, of the curved open scroll-work portion w, surmounted by an urn, P, of fanciful design.

What we claim as new is—

20 1. A design for a heating-stove, comprising the legs, the leg-base, the ash-pit section, the cylinder, and the top, all having the shape and ornamentation shown.

25 2. In a design for a heating-stove, the leg having its edges serrated and the center provided with the flame-shaped ornament f, as shown.

30 3. In a design for a heating-stove, the leg-base ornamented at the corners by curved beads and scroll-work on the sides, and the flame-shaped ornaments d beneath the end scrolls, as shown.

35 4. In a design for a heating stove, the ash-pit section ornamented by the foot-rail, and the bands ornamented by transverse ribbed portions, as shown.

5. In a design for a heating-stove, the ash-

pit door ornamented at the end by a scroll spreading out at its upper end and simulating the petals of a flower, as shown.

40 6. In a design for a heating-stove, the lower cylinder side plate having the ornamentation shown, consisting of the nondescript figure upon a large central scroll.

7. In a design for a heating-stove, the lower cylinder front plate having the ornamentation shown, consisting of a nondescript animal on a large central scroll, and with the representation of flame issuing from his mouth.

45 8. In a design for a heating-stove, the upper cylinder side plate having the ornamentation shown, consisting of a nondescript animal on a large central scroll and simulating in appearance part fish and part bird.

9. In a design for a heating-stove, the fire-door J, ornamented by the irregularly-arranged bars, and near its center by the plain band with the inclosed ribbed band, as shown, and straight bars extending from the plain band to the irregular bars.

55 10. In a design for a heating-stove, the body having the cylinder-plates shown, ornamented by the upper transversely-ribbed convexly-curved dividing-band, the lower reversely-curved band, and a plain edge between the two bands, as shown.

In testimony whereof we affix our signatures, in presence of two witnesses, this 2d day of April, 1888.

WILLIAM J. KEEP.
CHARLES WIPFLER.

Witnesses:

F. L. BROMLEY,
ISAAC S. FILER.
